(No Model.)

H. KEHL.
COAL DELIVERY BOX.

No. 535,250.

Patented Mar. 5, 1895.

UNITED STATES PATENT OFFICE.

HERMANN KEHL, OF NEW YORK, N. Y.

COAL-DELIVERY BOX.

SPECIFICATION forming part of Letters Patent No. 535,250, dated March 5, 1895.

Application filed April 30, 1894. Serial No. 509,564. (No model.)

To all whom it may concern:

Be it known that I, HERMANN KEHL, of New York city, in the county and State of New York, have invented a new and Improved 5 Coal-Delivery Box, of which the following is a full, clear, and exact description.

The object of the invention is to provide a new and improved coal delivery box, which is simple and durable in construction, and 10 more especially designed for supplying customers with coal in small quantities, and without danger of soiling the apartments on delivering or removing the coal from the box as needed for household purposes, at the same 15 time insuring the customer the proper amount of coal ordered.

The invention consists in certain parts and details, and combinations of the same, as will be hereinafter fully described and then 20 pointed out in the claims.

Reference is to be had to the accompanying drawings, forming a part of this specification, in which similar letters of reference indicate corresponding parts in all the views. 25 Figure 1 is a sectional side elevation of the improvement, on the line 1—1 of Fig. 3, showing the lid open and the discharge door closed. Fig. 2 is a similar view of the same, with the lid closed and the discharge door open. Fig. 30 3 is a plan view of the improvement with the lid open; and Fig. 4 is a sectional plan view of the discharge door and part of the vessel, on the line 4—4 of Fig. 2.

The improved coal delivery box is provided 35 with a casing A, preferably made of sheet metal, and formed with a straight flat back and a curved front, as plainly indicated in Fig. 3. On one side of the casing A is secured a suitable handle B, adapted to be taken hold 40 of by the coalman, to readily carry the filled box from the coal yard or coal wagon to the apartment of the customer, and to carry the empty box back for re-filling.

The vessel A is provided at its upper end 45 with a hinged lid C, adapted to be fastened in place on the vessel when in a closed position by a suitable key-lock D, of any approved construction, and provided with a hinged lid D' for closing the upper exposed part of the 50 lock at the time the vessel is filled with coal, to prevent dust and other impurities from passing into the interior of the lock. When

the vessel is to be closed, the hinged lid D' is swung inward and downward, as shown in Fig. 2, to permit of locking the lid C in place 55 on the vessel by the lock D.

In the lower part of the vessel A is arranged a chute E, extending from the back of the vessel downward and forward, as plainly indicated in the drawings. The lower end of this 60 chute E discharges upon a perforated false bottom F, arranged a suitable distance above the bottom of the vessel A, to form a dirt receiving compartment G, provided with a door H for removing impurities, such as dust, dirt, 65 &c.

In the back of the vessel A is arranged a coal discharge door I, hinged at its lower end to the back and adapted to give access to the space between the chute E and the perforated 70 bottom F. The door I is adapted to swing outward to open, and when open as shown in Fig. 2, then it is in perfect alignment with the perforated bottom F, to permit of conveniently removing coal from the perforated bottom F, by the use of a shovel or other device. 75 The door I is provided on its sides with flanges I', to prevent coal from falling off the open door I, and the inner ends of the said flanges are formed with hooks I² adapted to abut 80 against the inner surface of the back of the vessel A, at a time when the door I is swung open, so as to hold the latter in a horizontal position. See Figs. 2 and 4. The door I is adapted to be locked in a closed position by 85 a suitable locking device I³. See Fig. 1.

In the back of the door I of the vessel A, is arranged a vertically disposed slot A', covered by a transparent or translucent strip J, which extends from the upper end of the 90 chute E to the top of the vessel, as plainly shown in Figs. 1 and 2. By this arrangement the contents of the vessel A can be at all times examined, so as to permit the customer to see that he receives the proper amount of coal ordered, and also permits him to determine at 95 any time the amount of coal left in the vessel.

The device is used as follows: When the door I is closed and the lid C is open, as shown in Figs. 1 and 3, then the vessel A is filled 100 with coal, say fifty pounds, at the coal yard or other place, after which the lid C is closed and locked by the lock D and the vessel is then delivered to the customer. As the ves-

sel is closed, no dust, dirt, &c., will arise at the time of delivering the vessel with its contents in the apartment of the customer. At the same time the carrier of the vessel is not liable to soil his dress, hands, &c. The customer receiving the filled box can see on the transparent plate or strip J that the vessel is properly filled with the amount of coal ordered.

10 In using the device, the operator opens the door I, and swings the same in a horizontal position, as shown in Figs. 2 and 4, and then by the use of a shovel removes coal as desired from the perforated bottom F, it being understood that coal will pass in small quantities from the chute E to the front of the perforated bottom F, to be then removed from the latter at the door opening, over the door I.

Impurities such as dust, dirt, &c., contained 15 in the coal readily sift through the perforated false bottom F, to accumulate in the compartment G, from which they can be removed at the coal yard previous to filling, on the return of the empty box.

20 It is understood that heretofore, in cities and other places, coal has been delivered to apartments in bags, and such bags when filled with coal and delivered to a customer cause considerable dust to arise in the house and rooms

to which the bag is carried. With my device, no dust can arise either in the delivery or on the removal of the coal from the bags.

Having thus described my invention, I claim as new and desire to secure by Letters Patent—

35 1. A coal box provided with a screen like false bottom and a removable receptacle thereunder, the inclined plate E within the vessel, the door I hinged to swing down into the plane of the false bottom and allow the ready introduction of a shovel and side flanges I' on said door and provided at their inner or lower ends with lateral stop lugs I² to engage the inner side of the box when the door is in its open position, the false bottom being provided with slots into which the said stop lugs extend when the door is closed, substantially as described.

40 2. A delivery box, comprising a vessel adapted to contain a measured quantity of coal, a lid for the said vessel and adapted to be locked thereto, a lock for the said lid, and a hinged cover for the said lock, substantially as shown and described.

45 HERMANN KEHL.
